UNITED STATES PATENT OFFICE.

HUGH WATT, OF MELBOURNE, VICTORIA, AUSTRALIA.

MAIL-BAG LOCK.

No. 866,317.

Specification of Letters Patent.

Patented Sept. 17, 1907.

Application filed June 17, 1907. Serial No. 379,404.

To all whom it may concern:

Be it known that I, HUGH WATT, a subject of the King of Great Britain, residing at 82 William street, Melbourne, in the State of Victoria, Australia, have invented certain new and useful Improvements in Mail-Bag Locks; and I do declare the following to be a full, clear, and exact description of the invention, such as will enable others skilled in the art to which it appertains to make and use the same.

10 This invention has been devised to provide means for fastening the necks of mail bags and similar wallets or receptacles with mechanism which while carrying the label of the place of destination will form a tell tale or check against the fastening being tampered or interfered with.

In order that my invention may be the more easily understood reference may be made to the accompanying drawings in which—

Figure 1 is an elevation of mechanism embodying my invention. Fig. 2 a section of the closed or boxed portion of same, while—Figs. 3 and 4 are respectively front and back end views of the said boxed portions.

In these drawings A is a loop constructed of leather or spring steel or other suitable material of sufficient dimensions to surround the neck of the mail bag for example and terminating at each end in an eyelet A' said eyelets having through same on the one end a simple link A² leading into a specially constructed catch link B and from the other eyelet proceeds a link A³. The link A³ is of sufficient length to allow the catch link B to be passed through same so that it may rest on top of the eyelet link A². The catch link B consists of a link of wire flat at its front portion then descending at a right angle thereto for a short distance when one of its 35 downward members branches out to a right angle to the plane of the said link, that is to say the lower portion of the said catch link B is at right angles to its upper portion. This catch link B is sized to enter the check device box C; the box is constructed preferably of a plate 40 bent somewhat to the shape of a parallelogram about three and a quarter inches in length by about one and three-quarter inches in height and about half an inch in width. In the top of this box C is placed a bearing pin D forming the fulcrum of a lever E from the inner side

45 of which depends a connecting link or rod F centered by pin F' and joining at its bottom by a center bearing pin G with two arms H and J set lever-wise upon pin fulcrums H' and J' respectively and proceeding in opposite directions from one another the whole being so placed that when the top lever E is moved up or down the ends of these opposite levers H and J operate in the reverse direction. Referring to these two levers H and J the front one H is formed at its end with a hook shaped curve H² and sized to enter into the catch link B here-

inbefore mentioned, the lever being sufficiently long to proceed a slight distance outside the end of the box or casing C when the top or actuating lever E has been raised. The back lever J is provided with a slightly elongated perforation J² at its fulcrum pin J' to enable it to make good the differential radius brought about 60 during its operation. Its end J³ is curved upwardly and is sharpened with a knife edge and point so that in its radial movement from its top to its bottom position this knife lever J performs a tearing and cutting function. Referring to the top or actuating lever E its front 65 end is curved at its termination and provided with a recess K in its upper surface to receive and be held by a hinged staple or hasp L the latter being free (when the lever E is pressed slightly down against the action of a spring) to be moved by the forefinger and thumb out of 70 engagement with the said recess K in the lever E. A small spiral spring M is set in a circular corresponding box M' and provided with a guide washer M² on its top, upon which a lug pin E' depending from the end of the lever E may press so that the action of the spring M will 75 keep the lever E upward against the hasp or staple L when the latter is in the recess K. The other end of the actuating lever E terminates in an open eyelet E² arranged to surround a depending bent wire arm N the latter being provided with a stop block N' at its bottom and securely fastened at its top to a catch or bolt O.

The bolt O is provided with a downward formation around which is set a spiral spring P exercising compressive force to keep the bolt O in an upward or locked direction. Suitable guide plates are arranged around 85 said bolt O to keep the latter in its proper position. Engaging with this bolt O is an extending plate R' of a box shaped hinged end cap R the latter being hinged at its bottom R² and so arranged that when it is closed the bolt O hereinbefore mentioned locks the top R' in 90 such a way that it cannot be released except by undoing the hasp or staple L from its recess K upon the lever E and allowing the latter to release the bolt O as aforesaid.

Upon one side of the hinged end cap piece R are provided extended lugs R⁴ so placed that when they are closed they fix in position a horizontally hinged address plate S placed on one side of the box. This plate S may have either the address upon itself or act as an obscuring shutter of the address which is placed respectively either under or above its hinged line—for instance underneath the hinge line of the shutter the address "To Melbourne" may be written and above the said hinge line the words "To London" may be written.

Referring again to the box shaped hinged end cap R the front face of same has a small sheet of glass R⁵ let in it and provision is made by which a small strip of paper

or like material can be laid and held in position in a recess T in the inner face of the box and in view from the glass plate.

- In operating the invention the loop A is placed around the neck of the mail bag or other like receptacle. The link A³ is then passed over the catch link B, the latter is then passed on to the hook end H² of the lever H the label plate S properly adjusted to show the direction it is intended the bag should go, the actuating lever E pressed down home and the hasp or staple L passed over into the recess K in the said lever. A small strip of paper acting as a seal is then placed in the recess at T and the hinged cap R closed so that its catch portion R' snaps over the locking bolt O.
- 15 The mail bag cannot be opened except by undoing the hasp L at the end of the lever E thus causing the knife J² to cut the paper strip and so leaving the latter in a cut or torn condition to indicate that the apparatus or mail bag has been tampered with. The said strip of 20 paper will carry upon it the particular printed matter, check, numbers, letters, hieroglyphics or secret marks in use by the communicating post offices.

To prevent the actuating lever E being accidentally disengaged from the hasp L by any rough handling 25 which the mail bag or any other receptacle might receive during transmission, I may attach to the bottom of the inside of the box C a small snib or catch F² which is secured through a slot C' in the bottom of the box C to a flat knob F³ on the outside. One end of the snib 30 F² is normally kept under the end of the connecting link or rod F by the action of a spring F⁴. It will be seen that when the snib F² is in this position the lever E cannot be pressed down and so released from the hasp L. To release the lever it is necessary to press 35 back the snib F² from underneath the rod F and while it is held in this position the lever E can be disengaged as before.

I would have it understood that in lieu of the hinged 40 label plate S or in addition thereto, I may have insert cards or labels to slip in a guideway arranged on box C.

These latter will be used particularly when the device is to be employed with mail bags or similar receptacles used for foreign mails.

I claim—

1. In a fastening and label check device for mail bags and similar receptacles:—In combination—A loop A having links B and A³, a box or case C, a catch lever H, a seal cutting lever J, means for operating the said levers, a device to hold the seal, and an address plate, substantially as and for the purposes set forth. 45

2. In a fastening and label check device for mail bags and similar receptacles:—In combination—A box or case C, a loop A having links B and A³, a catch lever H, a seal cutting lever J, means for operating the said levers, a device for holding the seal, an address plate, said means for operating the levers H and J consisting of an operating lever E, connecting link F and slot J² and means 50 for securing and retaining the lever E in a closed position or for releasing same consisting of a hasp L, lug pin E', spring M and washer M², substantially as and for the purposes set forth.

3. In a fastening and label check device for mail bags and similar receptacles:—In combination—A box or case C, a loop A having links B and A³, a catch lever H, a seal cutting lever J, means for operating the said levers, a seal holder R having a catch extension piece R' and lugs R⁴ and in which is a transparent plate R⁵, a surrounding recess T, a spring catch bolt O having an arm N and stopper block N', an eyelet E² attached to the lever E and a hinged address plate S, substantially as and for the purposes set forth. 55

4. In a fastening and label check device for mail bags and similar receptacles:—In combination—A box or case C having thereon a snib or catch F² provided with a knob F³ and spring F⁴, a loop A having links B and A³, a catch lever H, a seal cutting lever J, means for operating the said levers, a seal holder R having a catch extension piece R' and lugs R⁴ and in which is a transparent plate R⁵, a surrounding recess T, a spring catch bolt O having an arm N and stopper block N', an eyelet E² attached to the lever E and a hinged address plate S, substantially as and for the purposes set forth. 75

In testimony whereof I have signed my name to this specification in the presence of two subscribing witnesses.

HUGH WATT.
